UNITED STATES PATENT OFFICE.

JOHN T. DAVIS, OF SAN FRANCISCO, CALIFORNIA.

DESIGN FOR A BRIQUET OF ARTIFICIAL FUEL.

SPECIFICATION forming part of Design No. 33,520, dated November 6, 1900.

Application filed August 7, 1900. Serial No. 26,202. Term of patent 14 years.

To all whom it may concern:

Be it known that I, JOHN T. DAVIS, a citizen of the United States, residing in the city and county of San Francisco, State of California, have invented and produced a new and useful Design for Briquets of Artificial Fuel, of which the following is a specification, reference being had to the accompanying drawings, forming part thereof.

- o Figure 1 is a perspective view of such a briquet, showing my design, a flat band appearing as projecting slightly beyond the circumference. Fig. 2 is an outline of its shape as seen in elevation, the flat band appearing as projecting slightly beyond the circumference and at the sides beyond the hemispherical surfaces. Fig. 3 shows its outline as seen in plan view.

As shown in the drawings, the leading features of my design consist in two oppositely-

disposed convex surfaces A and B, the baselines of which are continuous and circular and are connected by a continuous flat band C, projecting slightly beyond the circumference, as shown, the whole forming a figure 25 which, regarded through its major axis, is an oblate spheroid and through its minor axis a circle.

Having described my invention, what I claim as new, and desire to secure by Letters 30 Patent, is—

The design for a briquet of artificial fuel as herein shown and described.

In testimony whereof I have affixed my signature, in presence of two witnesses, this 1st 35 day of August, 1900.

JOHN T. DAVIS.
